CLAIM

The ornamental design for a woman nightdress, as shown and described.

DESCRIPTION

FIG. 1 is a front, left side, top perspective view of a woman nightdress showing my new design;

FIG. 2 is a front elevational view thereof;

FIG. 3 is a rear elevational view thereof; and

FIG. 4 is a right side elevational view thereof; and,

FIG. 5 is a left side elevational view thereof.

The broken lines depict environment that forms no part of the claimed design for the woman nightdress.

1 Claim, 5 Drawing Sheets
